which is pivotally attached to the door 7 by means of a suitable pivot 33.

By inspection of Fig. 1, it will be observed that a link 35 has its ends pivotally connected respectively to the levers 19 or 27. Consequently, as the operating lever 19 is rotated in a clockwise direction, as viewed in Fig. 1, to open the door 5, the link 35 rotates the operating lever 27 in a counterclockwise direction to open the door 7. Reverse movements of the levers reclose the doors. The structure of Fig. 1 thus far specifically described is well known in the art.

Operating forces are applied to the lever 19 through a link 37 which has one end pivotally connected to the lever 19 and its remaining end pivotally connected to a crank 39. The free end of the crank 39 is rigidly secured to a shaft 41. Consequently, as the crank 39 rotates in a clockwise direction from the position illustrated in full lines to the position 39a illustrated in dotted lines in Fig. 1, the doors 5 and 7 are opened. It should be noted that during this operation the crank 39 travels less than 180°. Also, because of the angular relationships between the crank and the link 37, if the crank rotates at a uniform angular rate, the doors move at low speeds adjacent their open and closed positions and with a substantially larger velocity adjacent intermediate positions.

Rotation of the shaft 41 is effected by an electric motor 43 through a suitable gear reduction 45. The electric motor 43 is provided with a suitable reversing control. For example, a push button may be provided to energize the electric motor for rotation in a first direction to open the doors. A second push button then may be provided to energize the motor for rotation in a reverse direction to close the doors. Since circuits for controlling door operating motors are well known in the art, a detailed discussion thereof is believed to be unnecessary.

The elevator car of Fig. 1 is designed for reciprocation in a shaft or hatch 47 which is shown in part in Fig. 2. As well understood in the art, the hatch extends in a vertical direction in a building to guide the elevator car between a number of floors. At each of the floors the hatch 47 is provided with a pair of hatch doors 49 and 51 which may be moved from the closed positions illustrated in full lines to the open positions 49a and 51a shown in broken lines. The door 49 is provided with hangers 53 and hanger rollers 55 for guiding the door along a horizontal rail 57 which is secured to the hatch. Similarly, the door 51 is provided with hangers 59 and hanger rollers 61 which guide the door 51 along the rail 57.

In order to assure movement of the doors 49 and 51 in unison, a pair of sheaves 63 and 65 are mounted for rotation adjacent the ends of the rail 57. A flexible cable 67 extends around the sheave 63 and has its ends connected respectively to one of the hangers 53 and one of the hangers 59. In a somewhat similar manner, a flexible cable 69 extends around the sheave 65 and has its ends connected respectively to one of the hangers 55 and one of the hangers 61. The flexible cables assure movements of the doors in unison in a manner well known in the art.

The doors 49 and 51 are resiliently biased towards closed position in any suitable manner. As illustrated in Fig. 2, a pair of links 71 and 73 are pivotally connected together. The free end of the link 73 is pivotally connected to the door 49 and the free end of the link 71 is pivotally

connected to a lug 75 which is secured to the hatch. A spring unit 77 is pivotally connected to the link 71 and to a lug 79 which is secured to the hatch. The spring unit 77 continuously urges the link 71 in a clockwise direction about the lug 75 for the purpose of urging the doors 49 and 51 towards their closed positions. The spring unit 77 may include a hydraulic check or shock absorber to prevent slamming of the doors. The spring unit 77 closes the doors if for any reason they are opened when the elevator car is not adjacent the associated floor. In addition, the spring unit tends to eliminate vibration which otherwise might be present during an opening or closing operation of the doors.

It is desirable that the same motor employed for operating the elevator car doors be employed for opening and closing the hatch doors 49 and 51. For this reason, mechanism is provided for connecting the elevator car and hatch doors when the elevator car is adjacent such hatch doors. As shown in Fig. 2, the door 49 is provided with a grooved block 81 which is positioned to receive slidably in the groove a vane 83 which is secured to one of the elevator car doors (the vane is shown in dotted lines in Fig. 2). As shown in Fig. 1, the vane 83 is elongated in the direction of travel of the elevator car. The relationship between the vane 83 and the grooved lock 81 is clearly shown in Fig. 3. As shown in Fig. 3, when the elevator car is adjacent a floor of the associated building the vane 83 is received in the groove 81a of the block 81. When the door 7 on the elevator car is moved by its associated electric motor 43, operating forces are also applied through the vane 83 and the groove block 81 to the door 49. Consequently, the same motor is effective for opening and closing both the elevator car and the doors and the hatch doors.

Since the hatch doors are accessible to the public at each floor of the building in which the elevator system is located, it is desirable that the doors be latched against unauthorized operation. For this purpose, a latch unit 85 is mounted on one of the hangers 53 (see Fig. 2) and a latch casing 87 is secured to the rail 57. Release of the latch unit is effected by rotation of a rod 89 which has an operating arm 91 and an operating roller 93 at one end thereof. Emergency release of the latch unit may be effected by arms A which are engageable by a removable operating key K. The construction of the latch unit 85 and the latch casing 87 will be understood from a study of Figs. 4 and 5.

Referring to Figs. 4 and 5, it will be observed that two latches 85a and 85b are mounted for rotation on a pin 95 which is secured to the hanger 53. The latch 85a has an arm 97 which cooperates with a stop pin 99 secured to the hanger 53 to permit a limited rotation of the latch 85a about the pin 95. The latch 85b may be provided with an arm (not shown) similar to the arm 97 for the same purpose.

The latch 85a has a lip 101 which cooperates with a rib 103 of the casing 87 to latch the doors against movement. As the doors approach closed position, a bevel 104 on the latch 85a rides over the rib 103 until the lip 101 drops to prevent an opening movement of the doors. In order to expedite operation of the elevator system, the lip 101 may be designed to drop over the rib 103 before the doors reached fully closed position. For example, the doors may be approximately two inches from fully closed position when the latch 85a drops to prevent a reopening of the doors.

During the continued closing operation of the doors, the lip 101 moves away from the rib 103 to the position illustrated in Fig. 5.

The latch 85b is designed to latch the doors in fully closed position. To this end, the latch 85b has a lip 105 which rides over the rib 103 and drops in the position illustrated in Fig. 5 just as the doors reach fully closed position.

In order to release the latches, a release lever 107 is pivotally secured by a pin 109 to the casing 87. This lever has a plate 111 positioned under the lips 101 and 105. Consequently, when the release lever 107 is rotated in a clockwise direction as viewed in Fig. 5, the plate 111 raises the lips 105 and 101 until the lips can be withdrawn over the rib 103.

It will be recalled that the release operation of the latches may be effected by rotation of the rod 89. This rod is rotatably mounted in suitable bearings 113 and 115 provided in the casing 87. The rod 89 carries a pin 117 which projects loosely through an opening 119 in the release lever 107. Consequently, suitable rotation of the rod 89 results in rotation of the release lever 107 to release the latches 85a and 85b.

Conveniently, one or more of the latches may be employed for operating an electric switch to provide a control for the elevator system. For example, in Figs. 4 and 5, the latch 85a has an insulating plate 121 secured thereto in any suitable manner as by a machine screw 123. The insulating plate 121 has a metal strip 125 secured to its lower face in any suitable manner. By inspection of Fig. 5, it will be observed that the metal strip 125 is positioned to engage the operating pin 127 of an electric switch 129. Consequently, as the lip 101 clears the rib 103 during a closing operation of the doors, the metal strip 125 drops to engage the pin 127 and operate the switch 129. It will be recalled that such operation occurs when the doors are approximately two inches from their fully closed position. The switch 129 may be in the control circuit for the elevator car to prevent movement of the elevator car until the latch 85a has entered the casing 87 to prevent opening of the associate doors. The switch will be discussed further below.

It will be recalled that the latches may be released by suitable actuation of the roller 93 to rotate the rod 89. The weight of the roller and arm 91 normally keep the rod in the position illustrated in Fig. 5. For the purpose of actuating the roller 93, a cam 131 is provided (see Figs. 1, 1a and 3). The cam 131 is secured to the elevator car by parallel links 133 (see Fig. 1a). Each of the links 133 is pivoted to the cam and to an angle member 135 which is secured to the elevator car. By inspection of Fig. 1a, it will be observed that the full lines show the cam 131 in retracted position. As the cam is lifted by means of a link 137, the links 133 approach a horizontal position and project the cam towards the broken line position 139 to actuate the roller 93.

The link 137 is actuated by means of a bell-crank lever 141 which is pivoted to a bracket 143 (see Fig. 1). The bracket 143 is secured to the top of the elevator car. The bell-crank lever 141 is rotated by means of a rod 145 which is pivotally connected thereto. The remaining end of the rod 145 is connected pivotally to an arm 147 which is mounted for rotation about the axis of a shaft 41 between stops 149 and 151. The shaft 41 is designed to actuate the arm 147 through a

slip coupling which is illustrated in detail in Fig. 6.

As shown in Fig. 6, the crank 39 has a male conical surface 153 which is positioned adjacent a mating female conical surface 155 formed in the arm 147. The arm 147 is resiliently biased towards the crank 39 by means of a coil spring 157 which is located between two washers 159 and 161. The washer 159 surrounds the shaft 41 and abuts a shoulder 41a formed on the shaft. Suitable friction material M may be located between the arm 147 and the adjacent surfaces of the crank 39 and the washer 161. Such material may take the form of leather or other materials commonly employed for facings of clutches or brakes. From the foregoing discussion, it is clear that the arm 147 is coupled to the shaft 41 through a slip friction clutch or slip coupling.

By reference to Fig. 1, it will be observed that the arm 147 has a limited angular movement. For example, a movement of 5° about the axis of the shaft 41 may suffice to move the cam 131 between its retracted and expanded positions. However, the slip coupling permits continued rotation of the shaft 41 to complete the opening or closing of the associated doors.

It will be recalled that the latch 85a shown in Fig. 5 is designed to operate a switch 129 about two inches before closure of the doors. If desired, a similar electric switch 165 (Figs. 7 and 8) may be associated with a latch 85b which corresponds to the latch 85b of Fig. 4. To this end, it may be necessary to space the parts to provide adequate room for the switch 165 but, except for the changes herein mentioned, the structure of the latch unit and casing otherwise remains the same as that described with reference to Figs. 4 and 5.

The latch 85b of Figs. 7 and 8 is similar to the latch 85b of Fig. 4 except that an extension 167 is provided for reception of an insulating plate 169. The insulating plate 169 is similar to plate 121 but may be somewhat shorter for the reason that it engages its associated switch 165 only when the doors are in fully closed position. The lever 107a corresponds to the lever 107 of Figs. 4 and 5 but is provided with a somewhat larger plate 111a because of the increased spacing between the latches 85a and 85b. When the structure of Figs. 7 and 8 is employed, the switches 129 and 165 are successively actuated as the doors approach their fully closed positions.

The arrangement of the switches 129 and 165 may be similar to that illustrated in Fig. 9. In Fig. 9 the hatch doors for the various floors are indicated by the labels, "Door 1" and "Door 2." It will be understood that the number of doors corresponds to the number of floors but it will be assumed, for the purpose of simplicity, that only two doors are served by the elevator car. The switches 129 and 165 of all the doors are connected in series with a car switch CS and the solenoid of a relay R between two conductors L1 and L2 which represents a source of direct current. The switches 129 and 165 for Door #1 are illustrated in detail. If Door #1 is open both of the switches 129 and 165 are open. As the door closes, the switch 129 closes in advance of the switch 165. It will be assumed that the relay R controls the starting circuit for the elevator car.

In order to permit either of the switches 129 and 165 to control in part the energization of the relay R, jumpers may be provided for shunting either of the switches. As shown in Fig. 9, a

single-pole double-throw switch 171 is provided. In the full line position of the switch 171, the contacts of the switch 165 are shunted and the contacts of the switch 129 are shunted in the dotted line position of the switch 171. With the switch 171 in the position illustrated in full lines, the switch 129 is effective for preventing energization of the relay R when the Door #1 is open. Since this switch closes when the door is approximately two inches from its closed position, the relay R is made effective for energization upon operation of the car switch before complete closure of the door.

With the switch 171 in its dotted line position, the switch 165 is effective for preventing energization of the relay R when the door 1 is open. Since this switch does not close until the door is substantially in its closed position, the relay R cannot be energized until the door is substantially closed. Such operation may be desirable under certain conditions, such as night operation of the elevator system.

It is believed that the operation of the system is apparent from the foregoing discussion. When the elevator car approaches a floor at which the doors are to be opened, a circuit is completed in a conventional manner for energizing the motor 43 to open the doors. Such energization may take place several inches in advance of the arrival of the elevator car at the desired floor. It will be understood that the cam 131 and the vane 83 have lengths sufficient to permit such advance energization of the electric motor.

In response to energization of the electric motor 43, the shaft 41 and the arm 147 are rotated in a clockwise direction as viewed in Fig. 1. The rotation of the arm 147 which may be through an angle of the order of five degrees is sufficient to advance the cam 131 to unlatch the doors. The five degree rotation of the shaft 41 necessary to unlock the doors may move the doors a distance of the order of $\frac{1}{16}$ of an inch. The mechanism has sufficient play to permit such movement of the doors.

Following completion of the movement of the arm 147, the shaft 41 and the crank 39 continue to rotate. Such rotation is permitted by the slip coupling connection between the arm 147 and the shaft 41. The rotation of the crank continues until the doors are fully open or until the doors are reversed.

As the doors open, the latches 85a and 85b leave their associated casing 87 and the switch or switches associated with the latches are opened. Consequently, the elevator car cannot be started until the doors have been reclosed to close the associated switches.

When the doors are reversed for a closing operation, the arm 147 promptly moves in a counter-clockwise direction as viewed in Fig. 1 to retract the cam 131. Such retraction of the cam releases the roller 93 and the roller by its weight and the weight of the arm 91 rotates the associated rod 89 to return the release lever 107 to the position illustrated in Fig. 5. As the doors close, the latches 85a and 85b successively close. If the switches 129 alone are effective as door interlock switches, when the doors for a floor at which the elevator car is parked are within two inches of being fully closed, the switch 129 associated therewith closes to condition the elevator car for further operation. As the elevator car leaves the floor, the doors continue to close until the latch 85b drops into latching position. The vane 83 has a length sufficient to permit this final closing

movement of the doors as the elevator car moves away from the associated floor.

A single latch 85c (Fig. 10) may be employed to perform the functions of both of the latches 85a and 85b. The latch 85c is mounted for rotation about a pin 95c which corresponds to the pin 95 of Figs. 4 and 5. An arm 97c cooperates with a stop pin 99c to limit rotation of the latch.

Two lips 101c and 105c are provided on the latch 85c. The lip 101c corresponds to the lip 101 of Figs. 4 and 5, and cooperates in the same way with the rib 103 of the casing 87c to latch the door against opening. The lip 105c corresponds to the lip 105 of Figs. 4 and 5. The lip 105c drops over the rib 103 just as the doors reach fully closed position to retain the doors in closed position.

During a door-opening operation, both lips of the latch 85c are guided over the rib 103 by raising the plate 111 in the manner discussed with reference to Figs. 4 and 5.

An insulating plate 121c of stepped formation is secured to the latch 85c and carries two electroconductive strips 125c and 125d. During a door closing operation the strip 125c drops upon two spring electrical contacts 129c just as lip 101c passes over the rib 103. The strip 125c and the contacts 129c constitute a switch (corresponding to the switch 129 of Figs. 4, 5 and 9) which completes a circuit when the doors are say two inches from fully closed position.

As the doors continue to close, the lip 105c finally drops over the rib 103 to bring the strip 125d into bridging relationship with two spring contacts 165c. The strip 125d and the contacts 165c constitute a switch corresponding to the switch 165 of Figs. 7, 8 and 9. The contacts 129c and 165c are secured to a suitable insulating block B.

Although the invention has been described with reference to certain specific embodiments thereof, numerous modifications thereof are possible. Therefore, the appended claims have been drafted to cover not only the modifications herein illustrated but also all other modifications falling within the spirit and scope of the invention.

I claim as my invention:

1. In a door assembly, a door, a supporting structure mounting the door for movement from a closed to an open position, an operating member, a support mounting the member for movement through a predetermined path, coupling mechanism responsive to movement of the operating member through the path for moving the door between the closed and open positions, a control element, translating means responsive to movement of the control element, and a slip coupling connecting the control element to the operating member, said slip coupling permitting movement of the operating member independently of the control element.

2. An assembly as defined in claim 1, wherein the control element is restricted to a path of movement substantially smaller than the predetermined path, and the translating means comprises a releasable door lock.

3. In a door assembly, a door, a supporting structure mounting the door for movement from a closed to an open position, an operating member, a support mounting the member for rotation through a predetermined angle, coupling mechanism responsive to rotation of the operating member through said predetermined angle for opening and closing the door, a control element, a slip coupling connecting the control ele-

ment to the operating member for rotation therewith, said slip coupling permitting movement of the operating member when the control element is restrained from movement, a door latch, and mechanism responsive to movement of the control element through an angle substantially smaller than the predetermined angle for actuating the latch.

4. A door assembly as defined in claim 3, wherein said coupling mechanism in response to rotation of the operating member in a first direction through the predetermined angle opens the door and wherein the coupling mechanism in response to the return of the operating member in a second direction through the predetermined angle closes the door, said operating element in response to movement in the first direction through a small portion of the predetermined angle releasing said latch, and said operating element in response to a return thereof through said small portion of the predetermined angle in the second direction conditioning said latch for a latching operation.

5. In a door assembly, a door, a supporting structure mounting the door for movement from a closed to an open position, a first latch for retaining the door substantially in closed position, a second latch for securing the door against an opening operation in response to arrival of the

door within a predetermined distance from closed position; and means mounting the latches for independent pivoted movement about a common axis.

5. In a door assembly as defined in claim 5, common means for releasing both of said latches to permit opening of the door.

10 6. In a door assembly as defined in claim 3 in combination with means cooperating with the door latch for latching the door in either of two different degrees of closure.

15 7. An elevator system comprising a door assembly as defined in claim 3 in combination with means cooperating with the door latch for latching the door in either of two different degrees of closure.

8. An elevator system as claimed in claim 7 in combination with switch means having circuit-controlling contacts opened and closed in response to operation of the latch.

LENNIUS R. RISSLER.
